UNITED STATES PATENT OFFICE.

FRANZ SCHRAIVOGL, OF ST. ALBANS, ENGLAND.

DESIGN FOR A VEHICLE-WHEEL.

44,497.

Specification for Design.

Patented Aug. 12, 1913.

Application filed September 9, 1912. Serial No. 719,433. Term of patent 8½ years.

To all whom it may concern:

Be it known that I, FRANZ SCHRAIVOGL, a subject of the King of England, and resident of St. Albans, Hertfordshire, England, have invented a new, original, and ornamental Design for Vehicle-Wheels, of which the following is a specification, reference being had to the accompanying drawing, forming part thereof.

The figure is a view in elevation of a wheel embodying my design.

I claim:—

The ornamental design for a vehicle wheel as shown.

FRANZ SCHRAIVOGL.
